CLAIM

The ornamental design for a hammock, as shown and described.

DESCRIPTION

FIG. 1 is a top, front, left side perspective view of the hammock according to my new design;

FIG. 2 is a top plan view thereof;

FIG. 3 is a rear elevational view thereof;

FIG. 4 is a left side elevational view thereof;

FIG. 5 is a front elevational view thereof;

FIG. 6 is a right side elevational view thereof;

FIG. 7 is a bottom plan view thereof;

FIG. 8 is a top front and left side perspective view of an alternative embodiment of the hammock according to my design, the trademark label removed;

FIG. 9 is a top plan view thereof;

FIG. 10 is a rear elevational view thereof, the front elevational view being a mirror image thereof;

FIG. 11 is a right side elevational view thereof, the left side elevational view being a mirror image thereof; and,

FIG. 12 is a bottom plan view thereof.

The broken lines showing the hammock supports in FIGS. 1 and 8 are for environmental purposes only and form no part of the claimed design. The broken lines within the hammock represent stitching.
